UNITED STATES PATENT OFFICE.

FERDINAND KOHOUT, OF ST. LOUIS, MISSOURI, ASSIGNOR TO ST. LOUIS CAR COMPANY, OF ST. LOUIS, MISSOURI, A CORPORATION.

TAPPING AND DRILLING MACHINE.

SPECIFICATION forming part of Letters Patent No. 760,878, dated May 24, 1904.

Application filed April 23, 1903. Serial No. 153,923. (No model.)

To all whom it may concern:

Be it known that I, FERDINAND KOHOUT, a citizen of the United States, residing in the city of St. Louis, in the State of Missouri, have invented certain new and useful Improvements in Universal Tapping and Drilling Machines, of which the following is a full, clear, and exact description, reference being had to the accompanying drawings, forming part of this specification.

My invention relates to an effective and simple machine for drilling and tapping holes.

My invention consists in features of novelty hereinafter fully described, and pointed out in the claims.

Figure I is a side view, part in section, illustrating my improved tapping and drilling machine. Fig. II is a vertical transverse section taken on line II-II, Fig. I.

Referring to the drawings, 1 represents a suitable framework in which is journaled a shaft 2, adapted to carry a drill 3 at one end and a tap-holding chuck 4 at the other end. The shaft 2 passes through journal-studs 5, carried by the frame 1. These studs support beveled pinions or wheels 6 and 7, with which mesh a beveled pinion or wheel 8, secured to the lower end of a vertical shaft 9. The shaft 9 may be turned either by a drill-press (not shown) applied to its upper end or by means of a counter-shaft 10, provided with a pulley 11 and which has a bevel-gear connection 12 with the shaft 9. As the shaft 9 is turned it will cause one of the beveled pinions 6 and 7 to be turned to the right and the other one to be turned to the left, these pinions revolving constantly so long as the shaft 9 is being turned. Keyed or otherwise secured to the shaft 2 between the beveled pinions 6 and 7 is a clutch 13, adapted to engage with either the beveled pinion 6 or the beveled pinion 7, according to which position it is in. I have shown the clutch in the form of a collar having pins on its opposite faces adapted to engage with pins projecting, respectively, from the faces of the beveled pinions 6 and 7.

Surrounding the shaft 2, between the clutch 13 and the beveled pinion 6, is an expansion-spring 14, which in the absence of endwise

pressure on the shaft holds the clutch 13 into engagement with the beveled pinion 7, and when the parts are in this position the drill 3 is being turned to the left or in the proper direction to drill a hole in a piece of metal placed between the drill-point and the rest 15. When the hole has been drilled, the piece of metal is moved to the chuck end of the shaft, and when pressure is applied that causes the metal to be forced against the tap (not shown) the spring 14 contracts, permitting the end-wise movement of the shaft 2 in the direction of the arrow and causing the clutch 13 to engage with the beveled pinion 6. This causes the shaft 2 to be turned to the right or in the proper direction for tapping a hole in the piece of metal that has been drilled. When the thread has been formed and the pressure is removed from behind the piece of metal, the spring 14 throws the shaft 2 back to the position shown in Fig. I, so that the clutch 13 will engage the beveled pinion 7, and the shaft now commences to turn to the left, thus unscrewing the tap and causing the drill-point 3 to form another hole in a piece of metal which has been placed in front of it against the rest 15. In this way the time of the machine is fully utilized, and it is entirely automatic in its operation. The perfect alignment of the shaft 2, the drill-point 3, and the tap carried by the chuck 4 reduces the danger of breaking drill-points and taps to a minimum.

The rest 15 is carried by a common form of slide mechanism 17, and when a hole has been tapped the movement of the rest 15 toward the drill 3 with the interposed piece of metal to be drilled acts to assist the spring 14 to move the shaft to and bring the clutch into engagement with the beveled pinion 7.

I claim as my invention—

1. In a tapping and drilling machine, the combination of a suitable frame, a shaft loosely journaled in the frame adapted to move endwise therein and provided at one end with means for carrying a drill and at the other end with means for carrying a tap, a pair of pinions, means for moving the pinions in opposite directions, and a clutch con-

- nected to said shaft and which is adapted to engage either one of said pinions according to the position of the shaft, substantially as set forth.
5. 2. In a tapping and drilling machine, the combination of a suitable frame, a shaft loosely journaled in the frame adapted to move endwise therein and provided at one end with means for carrying a drill and at 10 the other end with means for carrying a tap, a pair of pinions, a driving-shaft geared to said pinions and adapted to move the same in opposite directions and a clutch connected to the first-mentioned shaft and which is adapted 15 to engage either one of said pinions according to the position of its shaft, substantially as set forth.
3. In a tapping and drilling machine, the combination of a suitable frame, a shaft 20 loosely journaled in the frame adapted to move endwise therein and provided at one end with means for carrying a drill and at the other end with means for carrying a tap, a pair of pinions journaled to said frame 25 around said shaft, means for moving the pinions in opposite directions, a clutch secured
- to said shaft and which is adapted to engage either one of said pinions according to the position of the shaft, and a spring for exerting endwise pressure to said shaft in one direction, substantially as set forth. 30
4. In a tapping and drilling machine, the combination of a suitable frame, a shaft loosely journaled in the frame adapted to move endwise therein and provided at one 35 end with means for carrying a drill and at the other end with means for carrying a tap, a pair of pinions journaled to said frame around said shaft, a driving-shaft geared to said pinions and adapted to move the same in 40 opposite directions, a clutch secured to the first-mentioned shaft and which is adapted to engage either one of said pinions according to the position of its shaft, and a spring for exerting endwise pressure on the first-men- 45 tioned shaft in one direction, substantially as set forth.

FERD. KOHOUT.
